UNITED STATES PATENT OFFICE.

JOHN H. PURDY, OF NEW LONDON, OHIO.

TELEGRAPH-POLE.

SPECIFICATION forming part of Letters Patent No. 752,259, dated February 16, 1904.

Application filed June 15, 1903. Serial No. 161,568. (No model.)

To all whom it may concern:

Be it known that I, JOHN H. PURDY, a citizen of the United States, residing at New London, in the county of Huron and State of Ohio, have invented certain new and useful Improvements in Telegraph-Poles, Anchors for Telegraph, Telephone, and Electric-Light Poles, Fence-Posts, &c., of which the following is a specification.

This invention has relation to poles, posts, or like supports for electric wires, fences, and the like, said poles being constructed of pottery-ware, fire-clay, vitreous material, plastic composition, such as cement or concrete, metal, and the like. The pole is constructed of sections, which are spliced in any substantial manner, so as to form, in effect, a single durable support. When the sections of the pole are made of plastic material or earthenware, they are strengthened and made more serviceable by having embedded therein stout wires or rods to continue the post or pole in service in case of breakage until repairs may be conveniently made.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view of a telegraph-pole embodying the invention. Fig. 2 is a cross-section of the pole, showing wooden splice-bars connecting the sections. Fig. 3 is a section similar to Fig. 2, showing metal splice-bars of angular formation. Fig. 4 is a perspective view of a fence-post embodying the invention.

Corresponding and like parts are referred to in the following description and indicated in all the views of the drawings by the same reference characters.

The pole or like support may comprise any number of sections, according to its length and diameter, so as to admit of the parts being

conveniently handled. In cross-section the pole or support is of cruciform or winged formation, this construction having been found to give the best results both with respect to strength and lightness. To stiffen, strengthen, and increase the durability of the pole, stout wires or rods 1 are embedded therein, the same being distributed, so that each wing of the pole is supplied with a stay wire or rod. Notches 2 are formed in one or more of the wings and constitute steps to facilitate climbing of the pole. In the preferable construction the notches or steps 2 are formed in oppositely-disposed wings and are alternately arranged. The wings also provide convenient handholds. The sections comprising the pole when abutted are connected by splice-bars, which may be of wood or metal, the same being arranged in the angle formed between adjacent wings, and if needs be may extend the entire length of post or pole in sections. When the splice-bars are of wood, they are approximately of triangular form in cross-section, as shown most clearly in Fig. 2. When the splice-bars are formed of metal, they comprise angularly-disposed wings, as indicated most clearly in Fig. 3, said wings conforming to the angular space formed between adjacent wings. The wooden splice-bars are indicated at 3 and the metal splice-bars at 3". The ties 4 for connecting the splice-bars to one another and to the sections of the pole or support pass diagonally through the latter, thereby serving to draw the splice-bars close into the angles formed between the wings. This manner of connecting the splice-bars enables the fastening to be effected by two sets of ties, as will be readily comprehended. The ties 4 may be bolts, clips, or any type of fastener commonly employed for connecting parts in the erection of structures of any kind. The base or ground sections may be used as anchors for windmill-towers, bases for wood, metal, or any kind of telegraph, telephone, or electric-light poles and may be made of any length, size, and shape, as occasion may require. In Fig. 4 a base or ground section is utilized as a foundation for a fence-post 5, an upper portion of one of the wings being cut away to provide a flat side, against which the board 5 is secured.

by suitable fastening means. The lower end of the board is downwardly and outwardly beveled and the upper end of the wing cut away to form a step or support for a piece of board. This construction admits of the shedding of water and obviates the quick wearing away of the lower end of the board, which would result if its lower end were square and stepped upon a square shoulder.

10 Having thus described the invention, what is claimed as new is—

1. A pole or like support composed of sections, each section comprising corresponding wings, splice-bars fitted in the angles formed between adjacent wings, and ties connecting diagonally-disposed splice-bars to each other and to the sections of the pole, substantially as set forth.

2. A pole or like support composed of sections, each section comprising corresponding wings, splice-bars fitted in the angles formed between adjacent wings, each comprising corresponding wings conforming to and fitting snugly against the wings of the pole-sections, and ties passed through the angles formed between the wings of the splice-bars and connecting diagonally-disposed splice-bars to each

other and to the pole-sections, substantially as set forth.

3. A pole or post for electric light, telegraph or telephone wire support to be made of earth-ware, glass, concrete, cement, metal or any durable substance, composed of sections, each section comprising corresponding wings or flanges, and ties connecting diagonally-disposed splice-bars to each other and also securely connecting the sections forming them into a pole or post for the purposes before mentioned, its shape being cruciform, as set forth, with notches in its sides to be used as steps going to and from wire and cross-arms, substantially as set forth.

4. A post or pole support composed of sections snugly fitted together and secured by ties passed through the angles formed between the wings, and splice-bars firmly connecting the sections forming the post or pole, substantially as specified.

In testimony whereof I affix my signature in presence of two witnesses.

JOHN H. PURDY. [L. S.]
